JOHN HAYS HAMMOND, JR., OF GLOUCESTER, MASSACHUSETTS

SYSTEM AND APPARATUS FOR SECRET RADIO COMMUNICATION

Application filed March 17, 1928. Serial No. 262,365.

The invention relates to a system of radio communication wherein a carrier frequency is utilized which carrier frequency is modulated in accordance with a secondary carrier frequency which in turn has been modulated by an audio frequency. This system has come to be known as the double modulation system.

An object of this invention is to transmit messages of such a type that reception is impossible for an unauthorized listener not equipped with apparatus constructed in accordance with this invention.

It is a further object of this invention to simplify the apparatus and method necessary for secret radio communication.

Other objects of this invention will become apparent from the following specification taken in connection with the drawings.

Previously apparatus has been designed for secret radio communication which requires the use of some frequency shifting device requiring exact synchronism between the transmitter and the receiving apparatus.

This type of apparatus is open to very serious objections in that exact synchronism is not only seldom possible but nearly always impossible.

It is an object of this invention to obviate the necessity for synchronism between receiver and transmitter and yet prevent detection and reception of the signals transmitted in accordance with my method, by an unauthorized listener.

In accomplishing these objects, I have utilized a "B" frequency which has been designated to represent a secondary or supersonic lower frequency such as for example of the order of 50 kilocycles. This "B" frequency is multiplied by a distortion amplifier to produce a carrier frequency of say 500 kilocycles. Both the "B" frequency and the carrier frequency thus produced are wobbled the small amount of a few cycles per second by the expedient of wobbling the "B" frequency before production of the carrier frequency. A push-pull modulator is used for modulating the "B" frequency, which has been wobbled, by the audio frequency or "A" frequency. This will cause a suppression of the intermediate or

"B" frequency and produce in the output the two side bands.

The carrier frequency or harmonic of the "B" frequency is modulated by one of the side bands produced in the first modulation in a similar push-pull modulator which is, therefore, adapted to modulate the carrier frequency by the said side band and produce therefrom two additional side bands but suppress the carrier frequency. One of the side bands produced by this latter modulation is transmitted as well as the "B" frequency. Transmission of these two frequencies is accomplished over separate antennæ.

Thus it can be seen that transmission is accomplished over two very narrow frequency bands.

Reception is accomplished through a special receiver in which the "B" frequency is received distorted and multiplied to provide the carrier frequency. The side band transmitted is received, combined with the carrier frequency produced and again combined with the original "B" frequency transmitted and thus produces the audio frequency.

Having now briefly described my invention attention is invited to the accompanying drawings in which Fig. 1 illustrates the transmitter adapted to carry out the principles of my invention. Fig. 2 represents the relative location of the various frequencies bands involved in my transmission. Fig. 3 represents the receiver adapted to receive the transmission of a transmitter as shown in Fig. 1.

Referring now more particularly to Fig. 1, there is diagrammatically shown at 10 a thermionic oscillator tube having filament 11, grid 12 and plate 13, the former of which is adapted to be supplied by a current from the source 14, regulated in the usual and well-known manner. The grid and plate circuit of the thermionic device 10 are interrelated through the winding 16 a central point of which is connected to the filament lead and the plate circuit includes the high potential source 15. Shunted across the inductance 16 is the condenser 17 for determining the frequency of the oscillator and in parallel with said condenser 17 is a variable condenser 18 which is adapted to be varied cyclically by

the motor 19 connected to the lighting current or other suitable source of power and thus wobble the frequency generated at 10 from B to B+W. The output of the oscillator 10 is supplied through the biasing battery 20 to the grid 12 of the amplifier tube 21 included in the plate circuit of which is the high potential source 22. In series with the source 22 is the inductance 23 of the coupling 10 23—25.

The inductance 25 is included in the antenna circuit comprising said inductance, the ground 27 and the antenna 26. A third inductance 28 is also inductively related to the inductances 23 and 25, the use for which will be later pointed out.

The output of the amplifier 21 is fed through the filter 24 to the output transformer 29—30 in the grid return circuit of 20 the push-pull modulator comprising the thermionic devices 38 and 39. The audio frequency source or microphone 31 taken in connection with the potential source 32 is adapted to vary the current flowing through the 25 primary circuit 33 of the transformer 34 in accordance with voice frequencies and consequently vary the current flowing in the secondary 35 in such a manner that charges are impressed inversely upon the grids 12 of the 30 devices 38 and 39 respectively. Condensers 36 and 37 are connected across the halves of the secondary 35 as shown for the purpose of tuning the input circuits to the desired frequency. The output circuit of the push-pull 35 amplifier comprises the primary winding 41 and the high potential source 40.

Inductively coupled to the primary 41 is the secondary 42 the midpoint 43 of which is connected through the inductance 54 constituting the secondary of the coupling 53—54 40 to the filaments of the push-pull modulator comprising the thermionic devices 55 and 56. Across the halves of the secondary 42 are the condensers 44 and 45 for tuning the input 45 circuits to the desired frequency.

The thermionic device 46 is adapted to have impressed upon its input or grid 12 variations of a frequency generated by the device 10 and is overloaded in such a manner that it will act as a distortion amplifier or harmonic generator. The high potential source 51 and the choke 50 are shunted by the condenser 47 which is adapted to control the frequency produced in the output or plate circuit which includes also the plate 13 and the primary 48. Inductively coupled to the primary winding 48 is a secondary winding 49 adapted to supply the carrier frequency 60 to the modulators 55 and 56 through the filter 52 and a primary 53 inductively coupled to the secondary 54 as above described.

The output circuit of the push-pull modulators 55—56 is completed through the primary winding 58 of the transformer 59 and

the high potential source 57 in the usual and well-known manner.

Inductively coupled to the primary 58 of the transformer 59 is a secondary 60 included in the antenna circuit which comprises in addition the condenser 61, the antenna 62, and the ground connection 63.

Referring now more particularly Fig. 2 there is shown at 1 a graphic representation of the relative frequency produced by the generator 10 and at 2 a graphic representation of the frequency produced by the harmonic generator 46. At 3 and 4 are shown the upper and lower side bands respectively produced by the modulation of the carrier frequency by the "B" frequency produced by the generator 10 after modulation in the push-pull modulator 38—39 by the "A" frequency supplied through the microphone 31. 5 and 6 represent graphically the location of 85 the side bands produced in the push-pull modulator comprising the devices 55 and 56 by the modulation of the carrier frequency supplied by the thermionic device 46 by the side band transmitted through the transformer 41—42 in the input of said push-pull modulator device.

It will be noted that all of the frequencies except 1 and 6 indicated on this diagram are in dotted lines which represent that they are 95 not transmitted, the only frequencies being transmitted are B+W representing the secondary carrier frequency plus the amount of wobble deviation and the side band produced by the modulation of the carrier frequency 10 100 (B+W) by the side band produced by the modulation of B by the audio frequency or 11 (B+W)+A.

Referring now more particularly to Fig. 3 there is shown at 110 an antenna the circuit of 10 which includes the condenser 111, inductance 113 and ground 114. This antenna circuit is adapted to receive the intermediate carrier frequency B+W and transfer it by means of the inductance 113 coupled to the secondary inductance 115, to the oscillatory circuit including the said inductance and the condenser 116. The condenser 116 is adapted to tune this circuit to resonance and supply to the grid 13 of the device 117 the frequency B+W. The device 117 includes the filament 11 the grid 12 and the plate 13, the filament of which is adapted to be supplied in the usual manner by a current of low potential by the source 118. The grid return is completed through the inductance 119.

The output of the amplifier device 117 includes the resonant circuit 121 and the high potential source 120. The resonant circuit 121 is adapted to be tuned to the intermediate carrier frequency B+W and includes the condenser 122 and the inductance 123 which latter comprises the primary of the coupling 123—124 the latter of which is 130

connected to the grid 12 of the amplifier device 125.

The input or grid circuit of the device 125 includes a source of low potential 127 for properly biasing said grid. The circuit of the filament 11 of the device 125 includes the low potential source 126 the current supplied by which is adapted to be regulated in the usual and well-known manner. The output of the device 125 includes the resonant circuit 129 and the high potential source 128, the former of which comprises the inductance 131 and the condenser 130 for adjusting the frequency of said resonant circuit. The last named inductance 131 is inductively coupled to a secondary inductance 132 which is adapted to supply the grid 12 of the thermionic device 133 with the frequency of the secondary carrier $B+W$. Included in the grid circuit of the device 133 is a biasing battery 135 which is adapted to bias the grid of said device so that it will produce a harmonic in its output circuit. The filament 11 is adapted to be supplied in the usual and well-known manner by the low potential source 134.

The output of the device 133, which functions as a harmonic generator, includes the tuned circuit 137 and the high potential source 136. The circuit 137 is tuned to a frequency which is the same as the carrier frequency produced by the harmonic generator 46 of Fig. 1. This circuit includes the inductance 139 and the condenser 138 the former of which is inductively coupled to the input 140 of the filter 141. The filters 24, 52 and 141 are of the band pass types as disclosed in the patent to Campbell dated May 22nd, 1917, No. 1,227,113. The output of the filter 141 includes the inductance 142.

The antenna 143 includes in its circuit the capacity 145, the inductance 146 and the ground connection 147 and is adapted to receive the side band being transmitted by the antenna 62 of circuit 1. The inductance 145 in said antenna circuit is inductively coupled to the inductance 148 which with the condenser 149 comprises a closed oscillatory circuit.

The said oscillatory circuit is adapted to supply through the inductance 150, the grid 12 of the thermionic device 151 with the alternating potential corresponding to the side band frequency transmitted from the antenna 62 of Fig. 1. Completing the grid cathode circuit is the tap 158 of the potentiometer 159 connected across the filament circuit for supplying the filament 11. The low potential source 156 is adapted to supply the said filament of the device 151 through rheostat 157 in the usual and well-known manner. Included in the input to the grid element 12 of the device 151 is the inductance 150 inductively coupled to the output inductance 142 of the filter 141.

The output circuit of the device 151 in-

cludes the oscillatory circuit 160 and the high potential source 163. The oscillatory circuit 160 comprises the capacity 161 and the inductance 162 which former is adapted to adjust the frequency of the oscillatory circuit 160 to the secondary carrier frequency plus the audio frequency which is one of the side bands produced by the combining of the carrier frequency as produced by the distortion amplifier 133 and supplied through the filter 141 to the input of said device 151 and the side band transmitted through the antenna circuit 143—147.

Inductively coupled to the inductance 162 is the inductance 164 of the closed oscillatory circuit comprising, in addition to the inductance 164, the capacity 165. This circuit is likewise tuned to the side band produced by the device 151 and is connected through the inductance 171 to the grid 12 of the device 172; the oscillatory circuit 164—165 is connected to the filament 11 of the device 172 by means of the tap 166 of the potentiometer 173 which is connected across the filament leads of the said device 172. The source 156 supplies the filament 11 of the device 172 with the necessary current which is adjusted by means of the rheostat 174.

The inductance 119 is included in the grid circuit of the device 117 and is inductively coupled to the inductance 167 which in turn is connected to the input of device 168. The device 168 amplifies the frequency impressed upon the grid of said device and produces in the output, including the inductance 169 and the high potential source 170, a frequency which is the same as the secondary carrier frequency transmitted by the antenna 26 of Fig. 1. Inductively coupled to the inductance 169 is the inductance 171 included in the grid circuit of the device 172.

The output of the amplifier 172 includes the telephones 175 or other suitable recording or indicating instrument, and the high potential source 163, the former of which may be shunted by the condenser 176 as shown.

Having now described the apparatus for carrying out my invention, I will briefly describe its operation.

The generator 10, of Fig. 1 produces a frequency which is designated as the B frequency. This frequency is adapted to be varied within small limits by means of a rotary condenser 18. The augmentation of this frequency is represented by W . Thus there is produced by the generator 10, a frequency $B+W$ which frequency is amplified and filtered and supplied to the push-pull modulator comprising the devices 38 and 39. In this modulator the frequency $B+W$ is modulated by the audio frequency A producing the side bands $B+W+A$ and $B+W-A$. Inductively coupled to the output of this push-pull modulator is the input circuit of a second push-pull modulator comprising the 130

thermionic devices 55 and 56. The input circuit of this last mentioned thermionic push-pull modulator is adapted to be tuned to one of the side bands produced in the first

5 push-pull modulator as for instance, the frequency $B + W + A$. In the distortion amplifier or harmonic generator 36 a frequency $B + W$ produced in the generator 10 is adapted to be multiplied to a frequency such as 10 ($B + W$).

This harmonic frequency 10 ($B + W$) is supplied as the carrier frequency to the second push-pull modulator and is adapted to be modulated in the usual and well-known manner by the frequency existing in the input of said modulator as for instance $B + W + A$. The product of this modulation which suppresses the frequency 10 ($B + W$) is the side bands 10 ($B + W$) + ($B + W + A$) 15 or 11 ($B + W$) + A and 10 ($B + W$) - ($B + W + A$) or 9 ($B + W$) - A . The output circuit of the antenna 62 is adapted to radiate one of the side bands to the exclusion of the other. In this instance the side band represented as 11 ($B + W$) + A has been transmitted. The original secondary carrier frequency or $B + W$ is adapted to be transmitted also by the antenna 26, the circuit of which is tuned to resonance with the said frequency.

20 30 There thus exist in the ether, two frequencies of $B + W$ and 11 ($B + W$) + A , which, being properly combined in the receiver of my invention as illustrated in Fig. 3, will produce the original audio frequency.

35 The secondary carrier frequency $B + W$ is picked up by the antenna 110 and amplified through the amplifiers 117 and 125 and supplied to the distortion amplifier or harmonic generator 133, after which the frequency is filtered through the filter 141 and supplied to the input of the thermionic de-

40 tector 151. The antenna 153 is adapted to pick up the frequency 11 ($B + W$) + A and supply this frequency to the input of the de- 45 tector device 151. There is thus present in the input circuit of the device 151 the two frequencies 10 ($B + W$) and 11 ($B + W$) + A . This detector is so adjusted that in the output circuit there will exist the frequencies 50 $B + W + A$, and 21 ($B + W$) + A . The output circuit of the device 151 is tuned to the former of these frequencies, or $B + W + A$.

The input of the thermionic detector 172 is adapted to be supplied from the first detector 55 device with the frequency $B + W + A$ and also through the input of the secondary car- 60 rier frequency receiving circuit with the frequency $B + W$ through the amplifier 168. In this device 172 these two frequencies combine to produce the frequencies 2 ($B + W$) + A and A , the latter of which is adapted to actuate the receiver 175 and produce therein the original or audio frequency.

I have described above but one modifica- 65 tion of my invention. Other modifications

become apparent upon reading this disclosure and it is understood that I am not to be limited by the specific form shown, but rather by the scope of my invention as set forth in the appended claims.

I claim:

1. The method of secret radio communica- 7 tion which comprises generating a low supersonic frequency wave, wobbling the frequency of said wave, transmitting said wobbled low supersonic frequency wave, filtering said wobbled supersonic frequency wave, producing an audio frequency current to be transmitted, modulating said wobbled low supersonic frequency wave by said audio frequency current, suppressing the low supersonic frequency wave, and one of the side bands produced by said modulation, produc- 8 ing a harmonic of said low wobbled supersonic frequency wave and providing thereby a wobbled carrier frequency wave, filtering said wobbled carrier frequency wave, modu- 9 lating said carrier frequency wave by the remaining side band from said first mentioned modulation, suppressing the wobbled carrier frequency wave and one of the side bands produced by said last mentioned modulation, transmitting the remaining side band produced by said modulation, receiving the low wobbled supersonic frequency wave 9a transmitted, amplifying and producing from said wobbled frequency wave the wob- bled carrier frequency wave, receiving the side band transmitted, combining said side band and said wobbled carrier frequency 10 wave and detecting to produce said low wobbled supersonic side band, and combining said last mentioned side band with said transmitted low wobbled supersonic frequency wave and detecting to produce said 10 audio frequency current.

2. The method of secret radio communica- 11 tion which includes generating a low supersonic frequency wave, wobbling the frequency of said wave, transmitting said wobbled low supersonic frequency wave, filtering said wobbled supersonic frequency wave, producing an audio frequency current to be transmitted, modulating said wob- bled low supersonic frequency wave by said 11 audio frequency current, suppressing the low supersonic frequency wave and one of the side bands produced by said modulation, produc- 12 ing a harmonic of said wobbled supersonic frequency wave and providing thereby a wobbled carrier frequency wave, filtering said wobbled carrier frequency wave, modulating said carrier frequency wave by the remaining side band from said first mentioned modulation, suppressing the wobbled carrier frequency wave and one of the side bands produced by said modulation, and transmitting the remaining side band produced by said modulation.

3. The method of secret radio communica- 12

- tion which comprises receiving a low wobbled supersonic frequency wave, amplifying and producing from said wobbled frequency wave, a wobbled carrier frequency wave, receiving a side band, combining said side band and said wobbled carrier frequency wave and detecting to produce a low wobbled supersonic side band, combining said last mentioned side band with said transmitted low wobbled supersonic frequency wave, and detecting to produce an audio frequency current.
4. The method of secret radio communication which comprises generating a low supersonic frequency wave, wobbling the frequency of said wave, transmitting said wobbled low supersonic frequency wave, producing an audio frequency current to be transmitted, modulating said wobbled low supersonic frequency wave by said audio frequency current, suppressing the low supersonic frequency wave and one of the side bands produced by said modulation, producing a harmonic of said low wobbled supersonic frequency wave and providing thereby a wobbled carrier frequency wave, modulating said carrier frequency wave by the remaining side band produced by said first mentioned modulation, suppressing the wobbled carrier frequency wave and one of the side bands produced by said last mentioned modulation, transmitting the remaining side band produced by said modulation, receiving the low wobbled supersonic frequency wave transmitted, producing from said wobbled frequency wave the harmonic which constitutes the wobbled carrier frequency wave, receiving the side band transmitted, combining said side band and said wobbled carrier frequency wave and detecting to produce said low wobbled supersonic frequency side band, combining said last mentioned side band with said transmitted low wobbled supersonic frequency wave and detecting to produce said audio frequency current.
5. The method of secret radio communication which comprises generating a low supersonic frequency wave, wobbling the frequency of said wave, transmitting said wobbled low supersonic frequency wave, producing an audio frequency current to be transmitted, modulating said wobbled low supersonic frequency wave by said audio frequency current, suppressing the low supersonic frequency wave and one of the side bands produced by said modulation, producing a harmonic of said low wobbled supersonic frequency wave and providing thereby a wobbled carrier frequency wave, modulating said carrier frequency wave by the remaining side band produced by said first mentioned modulation, suppressing the wobbled carrier frequency wave and one of the side bands produced by said last mentioned modulation, and

transmitting the remaining side band produced by said modulation.

6. The method of secret radio communication which comprises generating a low supersonic frequency wave, wobbling the frequency of said wave, transmitting said wobbled low supersonic frequency wave, modulating said low supersonic frequency wave by an audio frequency current, producing a harmonic of said low wobbled supersonic frequency wave and providing thereby a wobbled carrier frequency wave, modulating said carrier frequency wave by one side band produced by said first mentioned modulation, transmitting one of the side bands produced by said last mentioned modulation, receiving the low wobbled supersonic frequency wave, producing from said wobbled frequency wave, the wobbled carrier frequency wave, receiving the side band transmitted, combining said side band and said wobbled carrier frequency wave and producing thereby a side band of said low wobbled supersonic frequency wave, and combining said last mentioned side band with said low wobbled supersonic frequency wave to reproduce said audio frequency current.

7. The method of secret radio communication which comprises generating a low supersonic frequency wave, wobbling the frequency of said wave, transmitting said wobbled low supersonic frequency wave, modulating said low supersonic frequency wave by an audio frequency current, producing a harmonic of said low wobbled supersonic frequency wave and providing thereby a wobbled carrier frequency wave, modulating said carrier frequency wave by one side band produced by said first mentioned modulation, and transmitting one of the side bands produced by said last mentioned modulation.

8. The method of secret radio communication which comprises generating a low supersonic frequency wave, independently transmitting said wave, modulating said wave by an audio frequency current, producing a harmonic of said wave and providing thereby a carrier frequency wave, modulating said carrier frequency wave by one of the side bands produced by said first mentioned modulation, transmitting one of the side bands produced by said last mentioned modulation, receiving the low supersonic frequency wave, producing from said wave the carrier frequency wave, receiving the side band, combining said side band with said carrier frequency wave, and thus producing a side band of said low supersonic frequency wave, and combining said last mentioned side band with said low supersonic frequency wave to reproduce said audio frequency current.

9. The process of secret radio communication which comprises generating a low supersonic frequency wave, independently

- transmitting said wave, modulating said wave by an audio frequency current, producing a harmonic of said wave and providing thereby a carrier frequency wave, 5 modulating said carrier frequency wave by one of the side bands produced by said first mentioned modulation, and transmitting one of the side bands produced by said last mentioned modulation.
10. The method of secret radio communication which comprises generating a wave of frequency B , wobbling said wave, by an amount W transmitting $B+W$, producing an audio frequency current A , modulating 15 $B+W$ by A and producing thereby $B+W+A$, $B+W-A$, and $B+W$, suppressing $B+W-A$ and $B+W$, producing a harmonic of $B+W$, $X(B+W)$, said last named wave to act as a carrier frequency wave, modulating 20 $X(B+W)$ by $B+W+A$, and producing thereby $(X+1)(B+W)+A$, $(X-1)(B+W)-A$, $X(B+W)$, transmitting $(X+1)(B+W)+A$, receiving $B+W$ and generating therefrom the harmonic $X(B+W)$, 25 receiving $(X+1)(B+W)+A$, and combining with $X(B+W)$ to produce $B+W+A$, and combining $B+W+A$ with $B+W$ to produce A .
11. The method of secret radio communication which comprises generating a wave of frequency $B+W$, transmitting said wave, generating an audio frequency current A , modulating $B+W$ by A and obtaining therefrom the wave $B+W+A$, producing a harmonic of $B+W$, $X(B+W)$, modulating $X(B+W)$ by $B+W+A$ and obtaining therefrom $(X+1)(B+W)+A$, transmitting the wave $(X+1)(B+W)+A$, receiving the wave $B+W$, transforming the frequency 35 $B+W$ into $X(B+W)$, receiving $(X+1)(B+W)+A$ and combining with $X(B+W)$ to produce $B+W+A$, combining said last mentioned wave with $B+W$ and producing therefrom the current A .
40. 12. The method of secret radio communication which comprises generating a wave of frequency $B+W$, transmitting said wave, producing an audio frequency current A , modulating $B+W$ by A and obtaining therefrom $B+W+A$, producing from $B+W$ the harmonic 10 $(B+W)$ modulating said harmonic wave 10 $(B+W)$ by $B+W+A$ and producing thereby 11 $(B+W)+A$ transmitting said last mentioned wave, combining and detecting the waves $B+W$ and the 11 $(B+W)+A$ to produce A .
45. 13. The method of secret radio communication which comprises modulating a low supersonic frequency wave by an audio frequency current, producing a harmonic of said low supersonic frequency wave and modulating said harmonic by the product of the first mentioned modulation, transmitting one of the side bands produced by said last mentioned modulation, and independently trans- 50 mitting said low supersonic frequency wave, and at a receiving station receiving the side band transmitted and the low supersonic frequency wave, producing the harmonic of said low supersonic frequency wave and combining with said side band to produce a wave which will combine with said low supersonic frequency wave to produce the audio frequency current. 70
14. The method of secret radio communication which comprises generating a low supersonic frequency wave, modulating said low supersonic frequency wave by an audio frequency current, producing a harmonic of said low supersonic frequency wave and modulating said harmonic by the product of 75 said modulation, and transmitting one of the side bands produced by said second named modulation, transmitting independently the low supersonic frequency wave, and at a receiving station combining said transmitted waves to reproduce said audio frequency current. 80
15. Apparatus of the type described for secret radio communication which comprises 85 means for generating a low supersonic frequency wave, means for wobbling the frequency of said wave, means for amplifying said wave, means for filtering said wave, means for providing an audio frequency current, push-pull means for modulating said supersonic frequency wave by said audio frequency current, means for transmitting said wobbled supersonic frequency wave, means for producing a harmonic of said wobbled 90 supersonic frequency wave, means for filtering said last named wave, push-pull means for modulating said harmonic frequency wave by one of the side bands produced by 95 said first mentioned modulation, means for transmitting one of the side bands produced by said last named modulation, means for receiving the wobbled supersonic frequency wave, means for amplifying said wave, means for producing a harmonic of said wave, 100 means for filtering said last mentioned wave, means for receiving the side band transmitted, means for combining the side band with said harmonic frequency wave, and producing therefrom a wave which when combined with said wobbled supersonic frequency wave will produce said audio frequency current, means for combining said last named wave with said wobbled supersonic frequency 105 wave to produce said audio frequency current. 110
16. Apparatus of the type described for secret radio communication which comprises 115 means for generating a low supersonic frequency wave, means for wobbling the frequency of said wave, means for amplifying said wave, means for filtering said wave, means for providing an audio frequency current, push-pull means for modulating said supersonic frequency wave by said audio frequency current, means for transmitting said 120

- wobbled supersonic frequency wave, means for producing a harmonic of said wobbled supersonic frequency wave, means for filtering said last named wave, push-pull means for modulating said harmonic frequency wave by one of the side bands produced by said first mentioned modulation and means for transmitting one of the side bands produced by said last mentioned modulation.

17. Apparatus of the type described for secret radio communication which comprises means for generating a low supersonic frequency wave, means for wobbling the frequency of said wave, means for providing an audio frequency current, means for modulating said supersonic frequency wave by said audio frequency current, means for transmitting said wobbled supersonic frequency wave, means for producing a harmonic of said wobbled supersonic frequency wave, means for modulating said harmonic frequency wave by one of the side bands produced by said first mentioned modulation, means for transmitting one of the side bands produced by said last mentioned modulation, means for receiving the wobbled supersonic frequency wave, means for providing a harmonic of said wave, means for receiving the side band transmitted, means for combining said side band with said harmonic frequency wave and producing therefrom a wave which, when combined with said wobbled supersonic frequency wave, will produce said audio frequency current.

18. Apparatus for secret radio communication which comprises means for generating a low supersonic frequency wave, means for wobbling the frequency of said wave, means for providing an audio frequency current, means for modulating said supersonic frequency wave by said audio frequency current, means for transmitting said wobbled supersonic frequency wave, means for producing a harmonic of said wobbled supersonic frequency wave, means for modulating said harmonic frequency wave by one of the side bands produced by said first mentioned modulation, means for transmitting one of the side bands produced by said last mentioned modulation, means for receiving the wobbled supersonic frequency wave.

19. Apparatus for secret radio communication which comprises means for generating a low supersonic frequency wave, means for modulating said supersonic frequency wave by an audio frequency current, independent means for transmitting said supersonic frequency wave, means for producing a harmonic of said supersonic frequency wave, means for modulating said wave by one of the side bands produced by said first mentioned modulation, means for transmitting one of the side bands produced by said last mentioned modulation, means for receiving the supersonic frequency wave, means for producing a harmonic of said supersonic frequency wave, means for combining said side band with said supersonic frequency wave to produce said audio frequency current.

20. Apparatus for secret radio communication which comprises means for generating a low supersonic frequency wave, means for modulating said supersonic frequency wave by an audio frequency current, independent means for transmitting said supersonic frequency wave, means for modulating a harmonic of said supersonic frequency wave by one of said side bands produced by said first mentioned modulation, means for transmitting one of the side bands produced by said last mentioned modulation, means for receiving the supersonic frequency wave, means for receiving the side bands transmitted and means for combining said side band with said supersonic frequency wave to reproduce said audio frequency current.

21. Apparatus for secret radio communication which comprises means for generating a low supersonic frequency wave, means for modulating said supersonic frequency wave by an audio frequency current, means for independently transmitting said supersonic frequency wave, means for modulating a harmonic of said supersonic frequency wave by one of the side bands produced by said first mentioned modulation and means for transmitting one of the side bands produced by said last mentioned modulation.

22. Apparatus of the type described which comprises means for generating a low supersonic frequency wave, means for wobbling the frequency of said wave, means for modulating said wobbled supersonic frequency wave by an audio frequency current, means for transmitting said wobbled supersonic frequency wave, means for modulating a harmonic of said wobbled supersonic frequency wave by one of the side bands produced by said first mentioned modulation, means for transmitting one of the side bands produced by said last mentioned modulation, means for receiving the supersonic frequency wave, means for receiving the side band transmitted, means for combining said side band with said supersonic frequency wave to produce said audio frequency current.

23. Apparatus of the type described which comprises means for generating a low supersonic frequency wave, means for wobbling the frequency of said wave, means for modulating said wobbled supersonic frequency wave by an audio frequency current, means for transmitting said wobbled supersonic frequency wave, means for modulating a harmonic of said wobbled supersonic frequency wave by one of the side bands produced by said first mentioned modulation, means for transmitting one of the side bands produced by said last mentioned modulation.

24. Apparatus of the type described which comprises means for generating a low supersonic frequency wave, means for wobbling the frequency of said wave, means for modulating said supersonic frequency wave by an audio frequency current, means for transmitting said supersonic frequency wave, means for modulating a harmonic of said supersonic frequency wave by one of the frequency bands produced by said first mentioned modulation and means for transmitting one of the side bands produced by said last mentioned modulation.

25. Apparatus of the type described which comprises means for generating a low supersonic frequency wave, means for wobbling the supersonic frequency of said wave, means for modulating said wobbled supersonic frequency wave by an audio frequency current, means for transmitting said wobbled supersonic frequency wave, means for modulating a harmonic of said wobbled supersonic frequency wave by one of the frequency bands produced by said first mentioned modulation, means for transmitting one of the side bands produced by said last mentioned modulation, means for receiving the wobbled supersonic frequency wave, means for receiving the side band transmitted, means for combining said side band with said wobbled supersonic frequency wave to reproduce said audio frequency current.

26. Apparatus for secret radio communication which comprises means for generating a low supersonic wobbled frequency wave, means for modulating said wobbled supersonic frequency wave by an audio frequency current, means for transmitting said wobbled supersonic frequency wave, means for modulating a high harmonic of said supersonic frequency wave by one of the frequency bands produced by said first mentioned modulation, means for transmitting the product of said last mentioned modulation, means for receiving the wobbled supersonic frequency wave, means for receiving the high frequency wave transmitted, means for combining said waves to reproduce said audio frequency current.

27. Apparatus for secret radio communication which comprises means for generating a low wobbled supersonic frequency wave, means for modulating said wobbled supersonic frequency wave by an audio frequency current, means for transmitting said supersonic frequency wave, means for modulating a harmonic of said wobbled supersonic frequency wave by one of the frequency bands produced by said first mentioned modulation, and means for transmitting the product of said last mentioned modulation.

28. Apparatus of the type described which comprises means for generating a low wobbled supersonic frequency wave, means for modulating said supersonic frequency wave by an audio frequency current, means for transmit-

ting said supersonic frequency wave, means for modulating a high frequency wave harmonic of said wobbled supersonic frequency wave by one of the frequency bands produced by said first mentioned modulation, and means for transmitting the modulated high frequency wave.

29. Apparatus of the type described having its frequency periodically varied between certain limits which comprises means for producing a low supersonic frequency wave, means for modulating said supersonic frequency wave by an audio frequency current, means for transmitting said supersonic frequency wave, means for modulating a high frequency harmonic of said supersonic frequency wave by one of the frequency bands produced by said first mentioned modulation, means for transmitting the modulated high frequency wave, means for receiving the low supersonic frequency wave, means for receiving the high frequency wave transmitted, means for combining said waves to reproduce said audio frequency current.

30. Apparatus of the class described having its frequency periodically varied between certain limits which comprises means for generating a low supersonic frequency wave, means for modulating said supersonic frequency wave by an audio frequency current, means for transmitting said supersonic frequency wave, means for modulating a high frequency wave harmonic of said supersonic frequency wave, by one of the frequency bands produced by said first mentioned modulation and means for transmitting the modulated high frequency wave.
